UNITED STATES PATENT OFFICE

122,137

DESIGN FOR A COMBINED ELECTRIC HEATING ELEMENT AND TERMINAL PLUG UNIT

Hoyt K. Foster, Hollis, N. Y., assignor to S. W. Farber, Inc., Brooklyn, N. Y., a corporation of New York

Application December 30, 1939, Serial No. 89,235

Term of patent 3½ years

To all whom it may concern:

Be it known that I, Hoyt K. Foster, a citizen of the United States, residing at Hollis in the county of Queens and State of New York, have invented a new, original, and ornamental Design for a Combined Electric Heating Element and Terminal Plug Unit, of which the following is a specification, reference being had to the accompanying drawing, forming part thereof, wherein—

Figure 1 is a plan view of the face of a combined electric heating element and terminal plug unit showing my new design, and

Fig. 2 is a rear plan view,

Fig. 3 is an end view looking at the right hand end of Fig. 2, and

Fig. 4 is a cross section on the line 4—4 of Fig. 1.

I claim:

The ornamental design for a combined electric heating element and terminal plug unit, substantially as shown.

HOYT K. FOSTER.
